UNITED STATES PATENT OFFICE.

THEODORE HAUSER, OF CHICAGO, ILLINOIS, ASSIGNOR TO THE GARVY COMPANY, OF CHICAGO, ILLINOIS, A CORPORATION OF ILLINOIS.

FOLDING BED.

SPECIFICATION forming part of Letters Patent No. 729,860, dated June 2, 1903.

Application filed December 4, 1901. Serial No. 84,637. (No model.)

To all whom it may concern:

Be it known that I, THEODORE HAUSER, a citizen of the United States, residing at Chicago, county of Cook, and State of Illinois, have invented a new and useful Improvement in Folding Beds, of which the following is a specification.

My invention relates particularly to the so-called "mantel-beds" or beds which in closing make two folds on transverse lines, so that when folded the bed lies substantially in a vertical plane and is of medium height, a curtain usually being employed in connection with a canopy for concealing the bed.

My primary object is to provide a bed of this character of improved general construction, particular attention being paid to securing compactness in the folded form and strength and rigidity in the extended form.

A minor object is to provide an improved caster connection for beds of metal construction.

In the preferred construction there are employed two side bars or rails, which fold on two transverse lines, four legs supporting the head-sections of said side rails and the adjacent ends of the intermediate sections of said side rails, two legs supporting the rear ends of said intermediate sections and supporting also the foot-sections of said side rails, and a supporting-frame pivotally connected with the intermediate set of legs and with the rear set of legs and serving to support spring-coils, which in turn support the woven-wire mattress between the ends thereof and serving also to fold said rear set of legs during the operation of closing the bed.

My invention is illustrated in its preferred form in the accompanying drawings, in which—

Figure 1 represents a side view of a bed in its extended or open position, the dotted lines indicating a position during the folding operation; Fig. 2, a view in side elevation of the bed in its folded position; Fig. 3, a view of the bed in its folded position looking toward that side of the bed which is away from the wall, a bottom plan view of the spring-supporting frame being presented in this view; Fig. 4, a view, partly in plan and partly in section, of the bed in its open position,

the section being taken as indicated at the lines 4 of Fig. 1; Fig. 5, an enlarged broken section taken as indicated at line 5 of Fig. 3 and showing the parts in the position they occupy in the completely-folded position of the bed; Fig. 6, a similar view showing the parts in the position which they occupy when the bed is partly open; Fig. 7, a similar view showing the position of the parts in the extended or open position of the bed, the dotted lines indicating the position of the foot-section of the bed before the same is extended; Fig. 8, an enlarged section taken as indicated at line 8 of Fig. 1 and showing a caster connection employed, and Fig. 9 a perspective view of a clip employed in the construction.

The preferred construction is as follows: A represents the head-section of the bed, B the intermediate section of the bed, and C the foot-section of the bed.

The head-section comprises side-rail sections *a*; a head-rail *a'*, connected with the rails *a* by braces *a''*; a head-standard *a'''*, supporting a canopy *a''''* and affording legs *a'''''*; an intermediate set of legs *a''''''*, connected by a rail *a''''''* and braces *a''''''''*, and braces *a''''''''''*, *a'''''''''''*, fixedly securing the side-rail sections *a* to the legs *a''''''''*, *a'''''''''*, respectively.

The section B comprises side-rail sections *b*, connected by pivots *b'* to the upper ends of the legs *a''''''* and the rear ends of sections *a*; legs *b''*, connected by pivots *b''''* with the rear ends of sections *b*; a cross-rail *b'''''*, rigidly connecting the legs *b''* at their upper portions, braces *b''''''* being employed in connection therewith, and a spring-supporting frame *b''''''''*, joined by pivots *b''''''''* to clips *b'''''''''''*, rigidly connected, respectively, with the legs *a''''''*, *b''*. The frame *b''''''''* comprises, preferably, an angle-iron forming the sides *b''''''''''*, *b'''''''''''* and the rear end *b'''''''''''*; an angle-iron *b''''''''''*, joining the front ends of the side members *b''''''''''*, *b'''''''''''*; cross members *b'''''''''''*, and a central longitudinal member *b'''''''''''*. As appears from Fig. 4, the angle-iron forming the sides *b''''''''''*, *b'''''''''''* has one inturned flange lying in a horizontal plane and one upturned flange, the inturned flange being notched at the corners *b'''''''''''* to permit bending.

The section C comprises side-rail sections *c*, connected at their front ends by pivots *c'*

to the rear ends of the rail-sections b and joined at their rear ends to a foot-rail c^2 , and a foot-piece c^3 , rigidly connected with the rear ends of the rail-sections c , braces c^4 being employed thereat.

Connected at its ends with the head-rail a' and foot-rail c^2 is a woven-wire mattress D , which is supported centrally upon coil-springs D' , carried by the frame b^6 . When the bed 15 is in the open position of Fig. 1, this wire mattress is tightly extended, and the direction of force applied to the foot-rail is such as to keep the foot-section C extended in a well-understood manner.

15 The manner in which the foot-section C is supported through its connection with the section B and the manner in which the bed is locked against collapse when in the extended position is clearly illustrated in Figs. 5 to 20 7, inclusive. As illustrated, the side-rail sections b have inturned upper flanges d and downturned flanges d' , the flanges d being cut away at their rear portions at d^2 . The members c have upper inturned flanges d^3 25 and downturned flanges d^4 , the latter being preferably notched at points d^5 . The front ends of the members c lie on the inner sides of the members b , and the pivotal connections c' between said members are through the downturned flanges $d^6 d^7$. The legs b^2 have forwardly-turned flanges d^8 and inwardly-turned flanges d^9 , the latter being cut away at their upper ends at points d^8 , Fig. 3, and recessed thereat at points d^9 , leaving projections d^{10} , to 30 which are rigidly secured angle-irons d^{11} . Each angle-iron d^{11} has a forwardly-turned arm d^{12} and a downwardly-turned arm d^{13} , the upper surface of the former serving to engage the flange d^3 of the member c to lock the bed 35 against collapse, as shown in Fig. 7. As indicated in Fig. 7, the inner end of the member c projects beyond the pivot c' , so that the inner end of the flange d^8 lies directly beneath the rear end of the flange d . The cut-away 40 portion of the flange d permits the foot-section of the bed to be swung upwardly to the position of the dotted lines of Fig. 7. In the position of Fig. 5 the front end of the flange d^3 (now become the rear end) engages the 45 lower end of the arm d^{13} . By reference to Figs. 1 and 7 it will be understood that were it not for the shoulders afforded by the arms d^{12} the bed might collapse by swinging rearwardly about the lower ends of the legs $a^6 b^2$, 50 as indicated by the arrows. In such case the head-standard a^3 of the bed would be lifted up and inclined toward the foot of the bed, as is evident. The shoulders afforded by the upper surfaces of the arms d^{12} effectually prevent any such action, inasmuch as the front 55 ends of the flanges d^3 are firmly locked between said shoulders and the rear ends of the flanges d . As shown in Figs. 5 to 7, inclusive, and Fig. 9, the clip b^{10} has a flange f , which 60 is secured by rivets f' to the flange d^7 of the leg b^2 and the flange f^2 , which receives the pivot b^8 . The rail b^4 is preferably of angle-

iron, having an upturned flange f^3 and a rearwardly-turned flange f^4 . The rear end member b^{13} of the spring-supporting frame b^6 has 70 an upturned flange f^5 and a forwardly-turned flange f^6 , the front edge of the flange f^6 lying beneath and in substantially the same plane as the rear edge of the flange f^4 . It will be observed that in swinging the bed upwardly 75 to the position of Fig. 6 and then to the completely-closed position of Fig. 5 the angle-iron b^{13} turns about the pivotal point b^8 , having a movement relatively to the angle-iron b^4 . In the operation of folding the bed the rear portion of the bed is commonly raised by lifting upon the member b^{13} . The disposition of the flanges of the angle-irons is such as to prevent the possibility of the fingers becoming caught between and injured by the angle-irons. In the extended position of Fig. 7 the notches d^5 of the flanges d^4 engage the notches d^9 at the upper portions of the flanges d^7 of the legs b^2 , thereby adding to the stability. 80

In the folded position the bed is supported 90 by the legs $a^5 a^6$, and said legs are therefore supplied with casters. The legs are composed of angle-irons with the outer surfaces of their flanges flush with the sides and ends of the bed, the lower ends of the flanges being curved 95 toward each other to afford sockets g , Fig. 8, for the shanks g' of the casters. The diameter of the socket is slightly less than the diameter of the shank, whereby the shank is 100 clamping held in place after being forced into the socket.

The canopy a^4 comprises, preferably, a fixed section h and a movable section h' , joined thereto by hinges h^2 . No curtain is shown connected with the canopy, though one is 105 commonly employed in connection therewith. When the bed is in the open position, the section h' of the canopy is folded back upon the section h , and when the bed is in the closed position the section h' is extended to the position of Fig. 2.

The manner of folding the bed is to first fold the foot-section C upwardly about the pivotal points c' and then lift the section B , during which movement the members b swing 115 about the pivotal points b' and the frame b^6 swings about the pivotal points b^7 . Thus there occurs in the section B a parallel link folding or collapsing action which carries the frame b^6 toward the plane of the rail-sections b , 120 thereby carrying the springs D' and mattress D inside the plane of the rail-sections b , as shown in Fig. 2. During this folding action the legs b^2 are swung downwardly to the folded position by the frame b^6 . When the 125 bed is open, the springs and mattress are chiefly supported directly from the legs $a^6 b^2$, the side rails of the bed being unconnected with the mattress. It will be understood that the folding operation can take place with the 130 usual woolen mattress and bedclothing upon the bed.

It will be observed that by reason of the collapsing action described the mattress may

occupy a low plane in the open position and the bed still be compactly folded in the closed position.

Changes in details of construction within 5 the spirit of my invention may be made. Hence no undue limitation is to be understood from the foregoing detailed description.

What I claim as new, and desire to secure by Letters Patent, is—

- 10 1. In a bed of the character described, having a stationary head-section and a swinging section connected therewith, a suitably-secured mattress, and a spring-supporting frame located below the plane of the mattress and comprising a part of said swinging section and having a movement toward the plane of the mattress during the closing operation, substantially as described. 70
- 15 2. In a bed of the character described, the combination of a stationary head-section having supporting-legs, a swinging section pivotally connected therewith and provided toward its foot portion with pivotally-connected 75 supporting-legs, a suitably-secured mattress, and a spring-supporting frame for said swinging section located beneath the plane of the mattress and supported directly from said legs and automatically moved parallel to itself in a folding movement during the operation of 80 closing the bed.
- 20 3. In a bed of the character described, the combination of a stationary head-section provided with rigidly-connected legs, a swinging section having side rails pivotally connected 85 with said head-section, legs pivotally connected with said side rails near the rear ends thereof, and a spring-supporting frame located beneath the plane of said side rails and pivotally connected at its front portion with 90 legs of said head-section and at its rear portion with said pivoted legs. 95
- 25 4. In a bed of the character described, the combination of a head-section provided toward the inner or rear portion thereof with rigidly-connected legs, intermediate side-rail sections pivotally connected at their front portions with the upper ends of said legs, legs pivotally connected with the rear portions of said rail-sections, a foot-section for said bed 100 pivotally connected with the rear ends of said rail-sections, a spring-supporting frame located beneath said rail-sections and pivotally connected to the legs at its front and rear ends, a mattress connected with the front 105 portion of said head-section and the rear portion of said foot-section and springs carried by said supporting-frame and supporting the central portion of the mattress. 110
- 30 5. In a bed of the character described, the combination of a stationary head-section having at its rear portion rigidly-connected legs formed of angle-irons, each having an in-turned flange, clips connected with said in-turned flanges some distance below the upper 115 ends of said legs, a spring-supporting frame pivotally connected with said clips, intermediate side-rail sections pivotally connected 120 with said head-section, legs pivotally connected with the foot ends of said rail-sections and comprising angle-irons, each having an in-turned flange, clips secured to said last-named in-turned flanges and pivotally connected with the rear end of said spring-supporting frame, a folding foot-section connected with said intermediate section, a mattress 125 connected with the rear portion of said foot-section and with the front portion of said head-section, and springs carried by said supporting-frame and bearing the central portion of said mattress. 130
- 35 6. In a bed of the character described, the combination of a head-section, an intermediate section foldably connected with said head-section, a foot-section foldably connected with said intermediate section, and locking-shoulders carried by the rear legs of said intermediate section and engaging suitable shoulders on one of the bed-sections serving to prevent collapse of the bed when the latter is in the extended position. 135
- 40 7. In a bed of the character described, the combination of a head-section having side-rail sections *a* and legs fixedly secured to the inner or rear ends thereof, side-rail sections *b* pivotally connected with said head-section 140 and having in-turned flanges, legs pivotally connected with the rear or foot ends of said sections *b*, means for closing said last-named legs during the operation of folding the bed, a foot-section comprising side-rail sections *c* pivotally connected toward their front or inner ends with the rear ends of the rail-sections *b*, and shoulders carried by said last-named legs and serving to engage the inner ends of the rail-sections *c* to prevent collapse 145 of the bed in the extended position. 150
- 45 8. In a bed of the character described having a head-section, an intermediate section foldably connected therewith, and a foot-section foldably connected with said intermediate section, legs foldably connected with the rear end of said intermediate section, and locking-pieces fixedly secured to the upper ends of said legs and having one set of shoulders serving to engage the front ends of said last-named rail-sections to lock the bed in the open position and another set of shoulders serving to engage said front ends in the folded position of said foot-section. 155
- 50 9. In a bed of the character described having a stationary head-section, an intermediate section foldably connected therewith, and a foot-section foldably connected with said intermediate section, and comprising suitable rail-sections, flanges on the rail-sections of 160 said intermediate section, flanges on the rail-sections of said foot-section engaging said first-named flanges to support said foot-section in the extended position, legs pivotally connected with the side-rail sections of said intermediate bed-section, means for folding said legs during the operation of closing the bed, shoulders carried by said legs and engaging said last-named flanges, thereby to 165

lock the bed in the extended position, and shoulders carried by the side-rail sections of said intermediate bed-section and by said legs for supporting said foot-section in the 5 folded position.

10. In a bed of the character described, having a head-section, an intermediate section foldably connected therewith, and a foot-section foldably connected with said intermediate 10 section, side rails for said intermediate section having inturned flanges cut away at their rear portions, side-rail sections for said foot-section pivotally connected with said intermediate rail-sections and having inturned 15 flanges engaging said first-named flanges, legs pivotally connected with the rear ends of said intermediate rail-sections and having inturned flanges located in a transverse plane, said flanges being cut away at their upper 20 portions to accommodate said rail-sections of said foot-section, and angle-irons each secured at one arm to a leg-flange and having a forwardly-projecting arm affording a shoulder bearing beneath the adjacent flange of 25 the adjacent side-rail section of said foot-section, and means for folding said legs during the operation of closing the bed.

11. In a bed of the character described, having a head-section, an intermediate section 30 foldably connected therewith, and a foot-section foldably connected with said intermediate section, side-rail sections for said intermediate section comprising angle-irons each having an inturned flange and a downturned 35 flange, the inturned flanges being cut away at their rear portions, side-rail sections for said foot-section comprising angle-irons each having an inturned flange and a downturned flange, the front ends of said last-named rail- 40 sections being located at the inner side of the rear ends of said first-named rail-sections, pivotal connections between the correspond-

ing rail-sections of said intermediate and foot sections, the inturned flanges of the rail-sections of said foot-section bearing beneath the 45 inturned flanges of said first-named rail-sections, legs pivotally connected with the rear ends of the downturned flanges of said intermediate rail-sections and comprising angle-irons having forwardly-turned flanges and 50 inwardly-turned flanges located in a transverse plane, said inwardly-turned flanges being cut away at their upper portions and notched adjacent to the cut-away portions to receive the downturned flanges of the rail-sections of said foot-section, the downturned flanges of said foot-section being correspondingly notched, and shoulders carried by said 55 inwardly-turned flanges of said legs and bearing beneath said inwardly-turned flanges of 60 said foot-section.

12. In a bed of the character described having a head-section, an intermediate section foldably connected therewith, and a foot-section foldably connected with said intermediate 65 section, legs pivotally connected at their upper ends with the rear ends of the rail-sections of said intermediate section, an angle-iron joining said legs and having a rearwardly-turned flange and an upwardly-turned 70 flange, and a spring-supporting frame for said intermediate section having side members pivotally connected with said legs and a rear angle-form member connecting the rear ends of said side members and having a forwardly- 75 turned flange and an upwardly-turned flange, said angle-irons being disposed to prevent injury to the fingers of the operator during the folding of the bed.

THEODORE HAUSER.

In presence of—

ALBERT D. BACCI,
WM. B. DAVIES.
